UNITED STATES PATENT OFFICE

157,941

FINGER RING

Vincent F. Colasuono, Brooklyn, N. Y.

Application August 19, 1946, Serial No. 132,646

Term of patent 3½ years

(Cl. D45—10)

To all whom it may concern:

Be it known that Vincent F. Colasuono, a citizen of the United States of America, residing at Brooklyn, in the county of Kings and State of New York, has invented a new, original, and ornamental Design for a Finger Ring, of which the following is a specification, reference being had to the accompanying drawing, forming part thereof.

Figure 1 is a front view of the finger ring.

Figure 2 is a side view of the finger ring.

Figure 3 is a plan view of the finger ring.

I claim:

The ornamental design for a finger ring, as shown.

VINCENT F. COLASUONO.
